VIBRATORY MACHINE

Ernst Ahlskog, Chicago, Ill.

Application April 18, 1941, Serial No. 389,117

9 Claims. (Cl. 121—3)

This invention has to do with a fluid actuated vibratory machine. More particularly it relates to a machine of portable character that is useful in abrading or polishing surfaces, though not restricted to such use.

The objects of this invention include the provision of:

A novel vibratory machine wherein there are work members oppositely reciprocal generally within a common plane and in out-of-phase relation to minimize vibration of the machine normally to said plane and to incur vibration within such plane;

An improved machine of the present class comprising juxtaposed pairs of fluid-driven motors connected with valve driving gear in such a manner that the valve means controlled thereby introduces propelling fluid to the motors in the proper sequence to cause concurrent operation of such motors in both pairs that work members respectively driven by said pairs of motors are simultaneously reciprocated in opposite directions;

A new valve and valve gear arrangement;

A new compact structure wherein valve drive gearing is disposed within a flywheel recess;

Improved means for preventing the device stopping on "dead center";

An improved clamp for detachably and firmly securing a polishing or abrading sheet onto a work member of the machine.

Other desirable objects inherent in and encompassed by the invention will later appear.

Referring now to the drawings:

Fig. 1 is a side elevational view of a preferred form of the invention the view being taken at the line 1—1 of Fig. 4;

Fig. 1a is a fragmentary view illustrating one of the clamp members of the machine and a shoe member associated therewith in an intermediate stage of assembly with a machine work member;

Fig. 2 is an end elevational view of the machine shown in Fig. 1;

Fig. 3 is a longitudinal vertical sectional view taken on the line 3—3 of Fig. 4;

Fig. 4 is a transverse vertical sectional view taken on the line 4—4 of Fig. 3;

Fig. 5 is a vertical sectional view taken at the plane indicated by the line 5—5 of Fig. 4; and

Figs. 6, 7 and 8 are horizontal sectional views looking downwardly and taken respectively upon the lines 6—6, 7—7 and 8—8 of Fig. 4.

The present machine is an improvement upon the machine of the same general character illustrated in my United States Letters Patent No.

2,214,189. One improved feature of this machine is in its employment of paired reciprocal work members, 10 and 11, instead of a single one of said members, these work members depending from and being longitudinally reciprocable by motor units presently to be described enclosed within a casing 12 which has a handle member 13 secured to its upper wall by standard fastening means such as screws 14. Generally in the operation of the device the work members 10 and 11 are caused to reciprocate in 180 degree out-of-phase relation; that is, each of the members reaches its oscillative limits simultaneously with that of the other but the movement of said members is always in opposite directions. Each of the members 10 and 11 carries a shoe member 15, secured thereto by clamps 16 which also serve to tautly hold a polishing or abrasive sheet 17 upon the shoes flatly against the lower faces of these shoes. Thus while the work members are reciprocated, the operator while holding the handle member 13 can press the portions of the sheets 17 that are upon the flat faces of the shoe members 15 firmly against the surface being treated, and can guide the machine for carrying the vibrating sheets onto the desired area of the surface undergoing treatment.

A motor and valve assembly comprising a valve block 18, Figs. 3, 4, 5 and 7, arranged generally transversely within a central portion of the casing 12 and a pair of cylinder blocks 19 and 20 extending lengthwise of the machine upon opposite sides of the valve block. Bolts 21, 22, 23 and 24 are inserted through respective holes in the valve block 18 and in flange portions of the cylinder blocks 19 and 20 and have nuts 25 turned upon their ends to hold the valve and cylinder blocks in assembly. The outer ends and sides of the cylinder blocks 19 and 20 are fitted snugly into the skirt portion of the casing 12 where the assembled parts 18, 19 and 20 are secured as by means of screws (not shown). A pair of cylinders 26 and 27 are formed in the cylinder block 19 whereas a pair of cylinders 26' and 27' are formed in the cylinder block 20. Pistons generally designated 28, 29, 28' and 29' are respectively within cylinders 26, 27, 26' and 27'. The outer end of each of the pistons is vertically slotted as indicated at 30, these slots 30 being aligned with slots 31 extending axially of and within both the upper and lower walls of each of the cylinders as 26. There is carried within each of the piston slots 30 a vertical bar 32 having a slightly vertically elongated opening 33. Such openings 33 in the bars 32 provide means for

connecting the bars with their respective pistons 28 by means of bolts 34 of which the shanks received by said openings have a diameter equal to the horizontal width of such openings. The vertical bars 32 associated with the pistons 28 and 29', together with a tie rod 35, Figs. 4, 5 and 6, serve as means for connecting the pistons 28 and 29' for movement in unison. In Fig. 5 it will be seen that the tie rod 35 has apertures in opposite of its ends which receive studs 36 projecting upwardly from the bars 32, nuts 37 being turned onto the upper ends of these studs for holding the bar 35 in fixed assembly with the bars 32 and hence with the pistons 28 and 29'.

A second tie rod 38 similar to the rod 35 is associated in like manner with the bars 32 which are connected with the pistons 29 and 29', there being additional studs 36 projecting upwardly from these bars. A nut 37 secures the right end of the rod 38, Fig. 6, upon the associated stud 36 whereas an internally threaded and headed member 41 in the form of a cap nut and having a shank serving as a wrist-pin for a connecting rod 106, secures the left end of the tie rod 38 upon the stud 36 (not shown) which projects upwardly from the bar 32 associated with the piston 29.

The work member 11, as will be seen in Figs. 4, 5 and 8, includes a substantially flat bottom plate 42 and an outer plate-like side wall 43. Thick boss-like sections 44 and 45 at opposite ends of the work member 11 are vertically drilled at 46 and 47 to respectively receive studs 48 and 49 which project downwardly from the bars 32 associated therewith, and nuts 39 and 40 screwed onto the lower ends of said studs 48 and 49 draw the upper faces of the bosses 44 and 45 into firm engagement with the lower ends of said bars 32 whereby the work member 11 is fastened securely with the reciprocal assembly including the pistons 28 and 29'.

The bosses 44 and 45 in the work member 11 are laterally drilled to receive axle shafts 50, 51, 52 and 53 upon which there are journaled a set of four rollers respectively designated 54, 55, 56 and 57. Clearance for these rollers is provided by recesses as 58 in the bosses as 44 so they will be free to rotate upon the axle shafts as 50. Smooth runways or tracks as indicated at 59 and 60 in Figs. 2 and 3 are formed upon the lower side of the cylinder block 20 for registration with the rollers 56 and 57. Similar tracks of which one is indicated at 61 in Fig. 3 are formed in symmetrical relation with the cylinder 26 upon the lower side of the cylinder block 19 and for respective cooperation with the rollers 54 and 55. It will be seen therefore that the rollers 54 to 57 will support the casing 12 and the parts contained within such casing as well as the force applied to the handle member 13 while the work member 11 reciprocates during operation of the machine.

A similar arrangement of rollers is provided for the work member 10, this member being constructed exactly like the work member 11 with the exception that it is a left-hand member whereas the member 11 is a right-hand member. Rollers 62, 63, 64 and 65 journaled upon axle shafts 66, 67, 68 and 69 in the member 10 and corresponding to the rollers 54 to 57 are adapted to bear and run along tracks as 59a and 60a upon the lower sides of the cylinder blocks 19 and 20 in spaced symmetrical relation with respect to the cylinders 27 and 27'. Studs 70 and 71 corresponding respectively to the studs 48 and 49 project downwardly from the bars 32 associated

with the pistons 29 and 29' into suitable openings in the bosses 72 and 73 of the work member 10. Nuts (not shown) threaded upon lower ends of the studs 70 and 71 cooperate therewith in holding the shoe 10 rigidly in association with the associated members 32 wherefore this work member is caused to reciprocate in unison with the pistons 29 and 29'.

Propelling fluid, which may be compressed air, is introduced into the machine through a passage 80 extending longitudinally through the cylinder block 20. The outer end of the passage 80 is enlarged and threaded for the reception of a coupling member as that shown at 81 in dotted outline in Fig. 1. The opposite or inner end of the passage 80 communicates with the fluid inlet chamber 82 in the valve block 18. This passage 82 communicates through inlet ports 83 and 84 respectively with the valve chambers 85 and 86 of which the chamber 85 together with a rotatable valve member 87 controls the admission and exhaust of propelling fluid to and from the cylinders 26 and 27' and of which the chamber 86 together with a rotatable valve member 88 control the admission and exhaust of propelling fluid to and from the cylinders 27 and 27'. Each of the valve chambers 85 and 86 is cylindrical, the chamber 85 having, in addition to the inlet port 83, a cylinder port 89 communicative with the cylinder 27', an exhaust port 90 and a cylinder port 91 communicative with the cylinder 26, whereas the valve chamber 86 has, in addition to the inlet port 84, cylinder ports 92 and 93 communicating respectively with the cylinders 26' and 27 and an exhaust port 94. In Fig. 4 the exhaust ports 90 and 94 will be seen to discharge into open spaces 95 and 96 between the ends of the valve block 18 and the skirt of the casing 12.

Upper and lower end portions of the valve members 87 and 88 are cylindrical, as illustrated in Figs. 4, 5 and 8, so they can be journaled in valve block bearings 97 and 98. The central portions of said valve members 87 and 88 are generally flat as shown in Figs. 5 and 7, these portions, however, being sufficiently thick that their narrow arcuate edges W, X, Y and Z have sufficient circumferential extent to completely cover any one of the ports as 89 in registry therewith.

The valve gear for driving the valve members 87 and 88 includes a rotatable unit consisting of a vertical shaft 100 extending through the bearing block 18, a small flywheel 101 integral with said shaft 100 at its upper end, and a flywheel 102 at the lower end of said shaft and secured thereto at a threaded section 103. The shaft 100 is rotatively supported within ball-bearing units 104 and 105 which are plainly shown in Figs. 3 and 4. Driving force is transmitted to the aforesaid rotatable unit by means of a pair of connecting rods 106 and 107 of which rods the rod 106 is driven from the pistons 29 and 29' and the rod 107 from the pistons 28 and 28'. Said wrist-pin nut 41, Fig. 6, has the left end of the connecting rod 106 journaled thereon whereas the right end of said connecting rod is connected eccentrically with the flywheel 101 by means of a threaded stud 108 having a slotted head 109 and a ball-bearing unit 110 disposed between the shank of the stud 108 and a large opening 111 in the connecting rod 106. An eccentric connection of the connecting rod 107 with the flywheel 102 consists of a threaded stud 112 having a slotted head 113 and a ball-bearing unit 114 disposed between the shank of

said stud and a large opening 115 in the left end of said connecting rod; see Fig. 3. In Fig. 5 the right end of the connecting rod 107 will be seen to be journalled upon a sleeve-like bearing portion 116 of the nut 40.

A gear 117, Figs. 3, 4 and 8 is connected non-rotatively with the shaft 100 by means of a pin 118, and this gear meshes with and drives gears 119 and 120, Figs. 4 and 8, which are non-rotatively connected with the lower ends of the valve members 88 and 87 by means of machine screws 121 and dowel pins 122.

The machine is regulated or adjusted for operation while rotating the drive gear 117 of the valve gear mechanism in the direction of the arrows A and B in Figs. 7 and 8, this direction being clockwise as viewed from above. Hereinafter referred to clockwise or counter-clockwise rotation of parts rotatable about vertical axes will also be considered from a viewing point above these parts. Such clockwise rotation of the gear 117 causes counter-clockwise rotation of the gears 119 and 120 and hence of the valve members 88 and 87.

Assuming the machine to be operating and at the cyclical stage illustrated in Fig. 7, the pressure fluid introduced into the machine through the passages 80 and 82 will be initially admitted through the inlet ports 83 and 84 and the cylinder ports 91 and 92 into the cylinders 26 and 26'. The trailing edge of the arcuate valve sections Y and Z at this time associated with the inlet ports 83 and 84 will have just uncovered these ports. Substantially concurrently with this uncovering of the inlet ports 83 and 84, the trailing edges of the opposite arcuate sections, W and X, upon the valve members 87 and 88 will have just uncovered the exhaust ports 90 and 94 and said valve members will have connected the cylinders 27 and 27' for exhaust respectively through the cylinder port 93, valve chamber 86 and the exhaust port 94, and through the cylinder port 89, valve chamber 85 and the exhaust port 90. Therefore, the pistons 28 and 28' will be free to move respectively to the right and left as viewed in Fig. 7 while the pressure fluid admitted to the cylinders 26 and 26' through the cylinder ports 91 and 92 acts against the heads of the pistons 28 and 28' for causing said pistons to move respectively to the left and to the right. The aforesaid movement of the pistons 28' and 28 respectively to the left and to the right simultaneously with such left and such right movement of the pistons 28 and 28' is effected by means of the aforesaid tie rods 35 and 38. The pairs of pistons 28 and 28' and 29 and 29' are also respectively connected for movement in unison by means of their associated work members 11 and 10.

During this movement of the pistons 28 and 29' to the left, the connecting rod 107 driven thereby will be effective for transmitting clockwise driving force to the flywheel 102. Likewise during the ensuing movement of the pistons 29 and 29' to the right, the connecting rod 106 driven thereby will transmit clockwise rotation to the flywheel 101 and thus augment the aforesaid driving force transmitted through the connecting rod 107 in driving the valve members 87 and 88. When the pistons 28 and 29' have reached the leftmost limit of their reciprocation and the pistons 29 and 29' have simultaneously reached their rightmost limit of reciprocation, the trailing edge of the arcuate

section W upon valve member 87 will have just uncovered the cylinder port 91 and the trailing edge and the arcuate section X upon the valve member 88 will have just uncovered the cylinder port 92 so that the exhaust of the cylinders 26 and 26' can occur through the ports 91 and 90 and 92 and 94. Concurrently, the trailing edges of valve sections Y and Z will have just uncovered the cylinder ports 89 and 93 so that the pressure fluid will be communicative with the cylinder 27' through the ports 83 and 89 and such pressure fluid will be communicative with the cylinder 27 through the ports 84 and 93 preparatory to reversing the pistons 29' and 29 for driving the same in the direction opposite to their just previous reciprocal movement and consequently the pistons 28 and 28' connected therewith through the tie rods 35 and 38 will also be reversed in their movement while exhausting the pressure fluid from their associated cylinders through the exhaust ports 90 and 94.

At this time the flywheels 101 and 102 and the drive gear 117 will have made a single revolution and the pistons will each have made a forward and return stroke in their operation. In accomplishing this the valve members 87 and 88 will have rotated one-half of a revolution, wherefore the driven gears 119 and 120 are twice the diameter of the drive gear 117. So far as concerns the valve gear drive unit consisting of the flywheels 101 and 102, the shaft 100 and the gear 117, and the pistons of the machine, one cycle of operation will now have been completed. However, a complete rotation or operating cycle of the valve members 87 and 88 will not be completed until a second revolution of the valve gear driving unit has occurred, but since the valve members 87 and 88 are symmetrical in shape, during the ensuing second half revolution thereof the pistons will be driven exactly in the manner above described and the machine will again reach the cyclical stage with all its operated parts in the position illustrated in the drawings.

Means for preventing the machine stopping with the connecting rods on dead center consists of helical contraction springs 125 and 126. The spring 125 is distended and connected between apertured ears 123 on the left ends of the tie rods 35 and 38 while the spring 126 is similarly disposed between apertured ears 123 upon the right ends of these rods. It will be noted that when the pistons are at either extreme limit of their operation the springs 125 will act thereon through the studs 36 and the vertical bars 32 in such a way as to urge them toward a mid-position. Thus the connecting rods 106 and 107 will be operated to cause rotation of the valve members 87 and 88 into position for admitting pressure fluid into those cylinders which will effect advancement of the machine when it is again connected with the pressure fluid source. By using springs arranged as the springs 125 and 126 their force is utilized in urging the machine to an off-center position from either of its oscillative limits while incurring a minimum amount of expansion and contraction of said springs during operation of the machine.

Lubrication of the machine is had by means of a passage 127 in the cylinder block 19, this passage having a fitting at 128 in its outer end and through which a lubricant may be forced into and through the passage 127 and thence

into a passage 129 formed between cylinder block 19 and the valve block 18, and through bores 130 to the ball-bearing units 104 and 105. Some of the lubricant will feed downwardly through the ball-bearing unit 105 onto the gears 117, 119 and 120.

Each of the work members 10 and 11 has a transversely arranged open sided bearing 131 in each of its two ends to cooperate with the aforesaid clamps 16 for holding one of the shoes 15 in association therewith. These clamps are bent into shape from a piece of sheet metal having a width substantially co-extensive with that of the work members. One end of each clamp is bent into a circular bearing section 132 disposable within a bearing 131 of a work member; see Figs. 1 and 1a. Said clamps 16 are generally U-shaped, having a lower leg 133 and an upwardly inclined leg 134 joining at a rounded gripping section 135. From the free end of the upper leg 134 a section of the sheet from which the clamp is formed is bent upwardly and lapped downwardly to effect a flange 136 which is apertured for receiving a threaded stud 137, there being one of the studs projecting outwardly from each end of the work members. Wing-nuts 138 are advanceable upon the threaded studs 137 for tightening the clamps 16 and holding the same in position upon the work members, and springs 139 may be placed upon the studs 137 between the flanges 136 and the ends of such work members for forcing the clamp 16 downwardly into the dotted line position illustrated in Fig. 1a when the wing-nuts are loosened and further to react against said nuts to hold the same in firm frictional engagement with the threads upon the studs 137 when the nuts are tightened and to thus serve as locking means to prevent loosening of the nuts during operation of the machine.

Each shoe 15, attachable to the work members 10 and 11 by means of the clamps 16, is made from a piece of sheet metal of substantially the same width as the work members, said piece having a generally flat main body portion 140 from the ends of which flanges 141 are bent angularly upwardly and additional flanges 142 are bent angularly inwardly. A layer 143 of pliable material such as rubber is adhesively or otherwise securely fastened to the outer face of the main body portion 140 of each shoe, and a plurality of leaf spring members 144 are associated with the main body portions of such shoes for engaging the lower face of their work members. These springs 144 may be formed integrally with the sheet metal body 140 by cutting tongues therein and bending the same upwardly.

While a shoe 15 is being assembled with its work member as illustrated in Fig. 1a, a sheet 17 of abrasive material or polishing material, as the case may be, may be placed over the bottom of the shoe and wrapped about its ends preparatory to being clamped tightly in place thereon by the clamp members 16 when the assembly is complete. Initially the ends of the sheet 17 are folded over and about the flanges 141 and 142 and tucked downwardly and inwardly along the inner faces of such flanges. Meanwhile, the wing-nuts 138 at the opposite ends of the shoe will have been loosened to permit the clamps 16 to drop downwardly into the position illustrated in dotted outline in Fig. 1a, thereby shortening the distance between their gripping sections 135 whereby these sections are disposable within the hook-like formations effective by the flanges 141 and 142, these clamp sections 135 then bearing

5 against the inwardly tucked end portions of the sheet 17. Then while pressing upwardly upon the shoe 15 and tightening the wing-nuts 138, the clamps 16 will be caused to pivot in their bearings 131 while increasing the distance between their gripping sections 135 to press the adjacent portion of the sheet 17 outwardly against the inner faces of the flanges 141 and 142 and upwardly against the inner faces of the flanges 142 to grip the sheet tightly between these parts and concurrently to carry the shoe into assembly with the work member.

10 Reinforcing members 146, between the legs 133 and 134 of the clamps 16 prevent distortion of the curvature on these clamps at their gripping sections 135, so that as the nuts 138 are tightened for finally drawing said sections 135 upwardly these sections are projected outwardly against the flanges 141 and 142 for holding the sheet 145 and drawing the same tautly across the bottom of the shoe 15.

15 During operation of the machine when the sheet 145 encounters elevational irregularities in a surface being treated, such sheet can yield to accommodate these irregularities both because of the resiliency in the yieldable layer 143 and because of the yieldability of the spring members 144.

20 A further important operating advantage of 30 this invention is obtained by the slight oscillative movement of the device about an axis normal to the surface being treated. Due to the rapid deceleration and acceleration of the work members respectively just before and just after reaching their reciprocal limits, their inertia causes a small amount of sidewise displacement of the work member ends, first in one direction and then in the other. This action is particularly useful when abrasive sheets are attached to the 35 device because the abrasive particles are thus shifted for cutting in a new path pursuant to each lengthwise excursion.

40 While I have herein shown and described a single embodiment for clearly disclosing and 45 illustrating the invention, it should be understood that the invention is not limited to this specific embodiment but rather comprehends other arrangements, details and structures falling within the spirit thereof.

50 I claim:

1. In a machine of the class described, a valve 55 block, a plurality of pairs of fluid actuated motors of which the motors in each pair are oppositely disposed with respect to said block and of which motors each includes a member reciprocal in a path parallel with similar paths of the members in the other motors, work members respectively connected with each pair of reciprocal members in said pairs of motors, said work members having working surface portions substantially in a common plane in parallelism with said paths of reciprocal movement, said valve block having passages for conducting a motor actuating fluid to and from said motors, valve core means in said 60 block for controlling the flow of fluid through said passages, valve gear means driven from at least one of said motors and connected with said valve core means for operating the same, pursuant to operation of the device, to direct such fluid through said passages alternately to the motors in each pair and in such phase relation that the paired reciprocal members connected with one work member are caused to move oppositely to a second pair of such members and the work member connected therewith.

2. In a machine of the class described, a valve block, fluid actuatable motor means including a reciprocal driven member, a second fluid actuatable motor means also including a reciprocal driven member which is reciprocable in a path laterally spaced from and parallel with the reciprocal path of the first driven member, work members respectively connected with said motor driven members, said work members having working surface portions substantially in a common plane in parallelism with the reciprocal paths of said driven members, said valve block having passages for conducting motor actuating fluid to said motor means, valve means in said block for controlling the flow of fluid through said passages, valve gear means for driving said valve means, said valve gear means comprising a unit journalled in said valve block and drive means connecting the motor driven members with said journalled unit to impart continuous rotation thereto during operation of the motor means, said valve means being operable by the thus driven valve gear to sequentially direct actuating fluid into said passages to cause said motor means to successively drive their respective driven members in opposite directions between the limits of their reciprocal movement, and said valve means operating to control the flow of fluid in said passages in such cyclical sequence that the motor means reciprocate the driven members and hence said work members in 180 degree out-of-phase relation.

3. In a machine of the class described, a valve block, a plurality of pairs of fluid actuated motors of which the motors in each pair are upon opposite sides of said block, each motor including a driven member of which all are reciprocable in respective of parallel paths, work members respectively connected with each pair of said driven members associated with said pairs of motors, said valve block having passages for conducting a motor actuating fluid to said motors, valve means in said block for controlling the flow of fluid through said passages, valve gear means for driving said valve means, said valve gear means comprising a unit journalled in said valve block and drive means connecting said motors with said journalled unit to impart continuous rotative movement thereto during the operation of said motors, said valve means being operable by the thus driven valve gear means to sequentially direct actuating fluid into such of said passages as to cause alternate operation of the motors in each pair for driving the work members in opposite directions between said reciprocal limits, and said valve means operating in such phase relation with said valve gear means that said motors reciprocate the work members in 180 degree out-of-phase relation.

4. In a machine of the class described, a valve block, a plurality of pairs of fluid actuated motors of which the motors in each pair are upon opposite sides of said block, each motor including a driven member of which all are reciprocable in respective of parallel paths, work members respectively connected with each pair of said driven members associated with said pairs of motors, said valve block having passages for conducting a motor actuating fluid to said motors, valve means in said block for controlling the flow of fluid through said passages, valve gear means for driving said valve means, said valve gear means comprising a unit journalled in said valve block and connecting rods drivingly connecting said pairs of motors with said journalled unit to im-

part continuous rotation thereto during operation of the motors and to cause said unit to rotate 180 degrees for each movement of the work members from each of their reciprocal limits to the other, said valve means being operable by the thus driven valve gear means to switch the flow of fluid through said passages at the conclusion of each 180 degree advance of said unit to cause alternate operation of the motors in each pair for reversing the direction in which the work members are driven, and said valve means operating to control the flow of fluid in said passages in such cyclical sequence that the motors reciprocate the work members in 180 degree out-of-phase relation.

5. In a machine of the class described, a valve block, a plurality of pairs of fluid actuated motors of which the motors in each pair are upon opposite sides of said block, each motor including a driven member of which all are reciprocable in respective parallel paths, work members respectively connected with each pair of said driven members associated with said pairs of motors, said work members having working surface portions substantially in a common plane in parallelism with the reciprocal paths of said driven members, said valve block having passages for conducting motor actuating fluid to said motors, valve means in said block and including valve core members rotatable about axes normal to the working surface portions of said work members for controlling the flow of fluid through said passages, valve gear means for driving said core members and comprising driven gears connected co-axially with said core members, a drive gear between and mutually meshed with the driven gears, a flywheel fixed for rotation with the drive gear and having a recess in a face thereof receiving all of said gears and a connecting rod drivingly connecting said flywheel with the driven members of a pair of said motors to impart continuous rotation to said flywheel, said gears and said valve cores during operation of the motors, said valve cores being operable when thus driven to switch the flow of fluid through said passages at the conclusion of each 180 degree advance of the flywheel to cause alternate operation of the motors in each pair for reversing the direction in which the work members are driven, and said valve cores being connected in such phase relation with the flywheel that the motors reciprocate the work members in 180 degree out-of-phase relation.

6. In a machine of the class described, a valve block, a plurality of pairs of cylinders of which those in each pair project endwise from opposite sides of said block, the principal axes of said cylinders being arranged in parallelism, paired pistons respectively reciprocal in each of said pairs of cylinders, work members respectively connected with each pair of pistons whereby the pistons of each pair are secured for reciprocation in unison, said work members having working surface portions substantially in a common plane spaced from said block and in parallelism with said cylinders, said valve block having passages for conducting motor actuating fluid to said cylinders for reciprocating the pistons therein, valve core members journalled in said block for rotation about axes normal to the plane of said working surfaces, one of said core members being operable when continuously rotated to alternately admit actuating fluid into the cylinders of one pair to cause reciprocation of the pistons therein and the other of said core members being similarly oper-

able with respect to a different pair of cylinders and pistons, valve gear means for driving said core members and comprising driven gears connected co-axially with said core members, a drive shaft journalled in said block for rotation about an axis between and parallel with said core members, a drive gear fixed to said shaft and mutually meshed with said driven gears, flywheels fixed upon said shaft at opposite sides of the valve block, one of said flywheels being disposed in the space between the work member surface portion and said block and being recessed to receive all of said gears, and connecting rods drivingly connecting said pairs of pistons respectively with said flywheels for imparting the aforesaid continuous rotation to the valve cores during reciprocation of the pistons, and said valve cores being connected in such phase relation with the flywheels that the pairs of pistons and the work members connected therewith are caused to reciprocate therewith in 180 degree out-of-phase relation.

7. In a machine of the class described, a plurality of work members having plane-like portions occupying substantially a common plane and reciprocable to shift said portions within said plane, a fluid motor for reciprocating said work members and including a valve block spaced from said plane-like portions, valve means in said block for controlling the flow of actuating fluid into said motor, and valve gear comprising gears within said space, a flywheel drivingly connected

with said gears and disposed flatwise in said space, said flywheel having a recess in a face thereof in which said gears are disposed, and means for driving the flywheel from the motor.

5 8. In a machine of the class described, fluid actuated motor means comprising driven members arranged side by side for reciprocation in parallel paths in 180 degree out-of-phase relation, valve means driven from said members and occupying such a stage in its operating cycle for directing actuating fluid into said motor means while said driven members occupy an intermediate position in their reciprocal paths, and contraction spring means connected between said driven members to constantly urge them into said intermediate position.

10 9. In a machine of the class described, a pair of work members arranged side by side for reciprocation in parallel paths in 180 degree out-of-phase relation, fluid actuated motor means comprising reciprocal driven members drivingly connected with said work members and in such cyclical relation with respect thereto that they are in position to be acted upon by actuating fluid 15 while said work members occupy an intermediate position in their path of reciprocal movement, and a contraction spring connected between said work members generally transversely of their reciprocal paths to constantly yieldingly urge said work members into said intermediate position.
